UNITED STATES PATENT OFFICE.

FRANZ FRIEDRICH WILLY STIELER, OF BERLIN, GERMANY.

DRYING APPARATUS.

1,079,673.

Specification of Letters Patent.

Patented Nov. 25, 1913.

Application filed December 28, 1912. Serial No. 739,119.

To all whom it may concern:

Be it known that I, FRANZ FRIEDRICH WILLY STIELER, a subject of the King of Prussia, residing at Berlin, in the Kingdom 5 of Prussia and German Empire, have invented certain new and useful Improvements in Drying Apparatus, of which the following is a specification.

For the purpose of drying liquids by 10 means of drying drums it is usual either to allow the drum to dip into the liquid to be dried or to apply said liquid to the drum by means of rolls, a squirt, or the like. Such devices have however not been found to answer the purpose, because the liquid is not uniformly applied to the drum. This drawback is overcome according to the present invention by the liquid being applied by one or more floats, each of which is arranged in 15 a vessel provided adjacent to the drying drum.

In the accompanying drawing several constructions of the device are shown by way of example: Figure 1 representing, in 20 cross section, a construction having one float, Fig. 2 a plan of the same, the drum being shown in dot and dash lines. Fig. 3 is a cross section of a construction having two vessels in each of which a float is provided. Fig. 4 is a similar section through a device having one float provided with pins, the wall of the vessel containing said float being pressed against the drum. Fig. 25 5 shows a plan of the construction shown in Fig. 4. Fig. 6, a section through the device shown in Fig. 4 on a larger scale. Fig. 7 is a similar section of a modified construction of the device shown in Fig. 6. Fig. 8 is an enlarged detail sectional view of the 30 float shown in Figs. 5 and 6, and Fig. 9 is a partial plan view, enlarged, of said float.

In front of the hot drying drum *a*, which rotates in the direction of the arrow *w*, is provided a vessel *b*, the trough *c* of which 45 is supplied with liquid from the vessel *d* through the pipe *e*. The pipe *e* extends throughout the entire width of the vessel near to the bottom thereof, and has a number of perforations opening downward, so 50 that the material to be dried rises on both sides of the pipe *e* and mixes the liquid in the vessel *d*, which liquid accordingly receives a uniform temperature, in spite of the heat taken up unequally from the 55 drum *a*.

On the liquid in the trough *c* there is a

float *f* extending along the entire width of the drum *a*. The float can consist of one or more parts, and can be made of any specially light material, preferably of wood. 60 The edge *g* presses against the drum *a* and causes the material to be dried to be uniformly applied to said drum. Moreover this float renders it impossible for a skin or froth to be formed, so that the liquid can always uniformly approach the drum. 65

According to Fig. 3, the vessel *b* has two troughs *c*¹ and *c*², each of which is supplied with the material to be dried from a special vessel *d*¹, *d*² through the pipes *e*¹, *e*². In 70 each of said troughs there is a float *f*¹, *f*². By the consecutive action of the two floats *f*¹ and *f*² a more uniform application of the material to the drum is obtained.

In the construction shown in Figs. 4-6, 75 the material to be dried is contained in a trough *h*, the wall *k* of which is made of elastic thin sheet metal, and is adapted to be pressed more or less against said drum by means of the screws *l*. By means of this 80 arrangement a quite uniform pressure of the wall *k* against the drum *a* is obtained. As the thickness of the layer applied to the drum depends essentially on the intimate contact between said drum and the edge of 85 the wall *k*, the entire feed to the drum can be rendered very uniform over the entire width of the drum by adjusting the pressure of said wall. In order to still further improve the feed, the float *m* can be provided with short pins *n* along the edge adjacent to the drum. As shown in Figs. 6 and 90 8, the upper edge *o* and the pins *n* press against the drying drum *a*. These pins assist in distributing the material passing to 95 the edge *o*, so that a uniform distribution of the liquid is obtained under all conditions. The length of the pins is adjustable, so that with different depths of dip of the slide, according to the specific gravity of the liquids in question, the contact of the pins 100 with the drum *a* can be always maintained. The feed to the trough *h* is effected, as in the other constructions, through a pipe *p*, which communicates with a receiver *q*, and 105 extends over the entire width of the trough *h*. The pipe *p* is also in this case provided with openings directed downward, in order to maintain a uniform temperature of the liquid in said trough. The float *m* and the 110 feed pipe *p* can be connected together, for example, in such a manner that the feed

pipe is suspended from the float. Such an arrangement is shown in Fig. 7. This arrangement has the advantage that the trough can be quickly and conveniently exposed, for example, for cleaning.

What I claim and desire to secure by Letters Patent of the United States is:—

1. In a cylinder evaporator, the combination of a drying drum, a vessel adjacent to the periphery of said drum to contain the liquid to be dried, and a float supported on the liquid in position to feed said liquid to said drum.

2. In a cylinder evaporator, the combination of a drying drum, a vessel positioned adjacent the periphery of said drum in position to feed liquid to the latter, and a float supported on the liquid contents of said vessel with an edge in such close proximity to said drum periphery as to feed said liquid contents to the drum.

3. In a cylinder evaporator, the combination of a drying cylinder, a means for supporting a liquid supply adjacent the periphery of said cylinder and a means floated on the liquid in such close proximity to said cylinder as to feed said liquid gradually to the latter.

4. In a cylinder evaporator, the combina-

tion of a drying drum, a vessel adjacent to said drum containing a liquid to be dried and pressing against said drum, a float contained in said vessel, and pins along the edge of said float adjacent to said drum, substantially as, and for the purpose, set forth.

5. In a cylinder evaporator, the combination of a drying drum, a vessel adjacent to said drying drum, a float contained in said vessel, and a feed pipe passing throughout the entire width of said vessel and having downwardly directed perforations, substantially as, and for the purpose, set forth.

6. In a cylinder evaporator, the combination of a drying drum, a vessel adjacent to said drying drum and adapted to contain a liquid to be dried, a float contained in said vessel, and a pipe extending into said vessel and adapted to be supported by said float, substantially as, and for the purpose, set forth.

In testimony whereof I have signed my name to this specification in the presence of two subscribing witnesses.

FRANZ FRIEDRICH WILLY STIELER.
